UNITED STATES PATENT OFFICE.

EDWARD A. MCGINNIS, OF PITTSBURGH, PENNSYLVANIA.

ELECTRIC HAIR-WAVING APPARATUS.

Application filed May 4, 1926. Serial No. 106,655.

My invention relates broadly to electric hair waving apparatus but more particularly to an improved retention spring for maintaining the adaption rod in the assembled 5 position in the heating tube during the hair waving operation.

The retention springs, now commonly employed for the purpose above mentioned, are comparatively frail and invariably destroyed 10 by distortion when the adaption rod is removed from the heating element, thereby necessitating the replacement of the retention spring after each hair waving operation.

Important objects of my invention are to 15 provide a device of the type stated, in a manner as hereinafter referred to, which will automatically tighten itself in the adaption rod and in the heating tube of the apparatus, when the former is inserted in the 20 latter, which is simple in its construction and arrangement, strong, durable and efficient in its use, conveniently detachable from the adaption rod, and comparatively inexpensive to manufacture.

With the foregoing and other objects in view which will appear as the description proceeds, the invention resides in the combination and arrangement of parts and in the details of construction hereinafter described and claimed, it being understood that 30 changes in the precise embodiment of the invention hereinafter disclosed can be made within the scope of what is claimed without departing from the spirit of the invention.

In the drawing wherein like numerals of reference designate corresponding parts throughout the several views:—

Figure 1 is a vertical cross sectional view 40 of a heating element of an electric hair waving apparatus, provided with a retainer spring constructed in accordance with the invention.

Figure 2 is a side view of the retainer spring.

Figure 3 is an enlarged side view of the 45 retainer spring mounted in position in the adaption rod, the latter being in cross section.

Referring in detail to the drawing 1 50 notes a heater of an electrical heating apparatus commonly employed for permanently waving hair. The heater 1 comprises the heating tube 2 which carries the heating element 3. The latter is enclosed in a suitable 55 casing 4 fixed in position to the heating tube 2.

The tubular adaption rod 5, adapted for coiling thereon the hair to be waved, is inserted in the heating tube 2. The adaption rod 5 is maintained in the inserted position 60 in said heating tube 2, during the hair waving operation, by means of my improved retention spring 6.

The retention spring 6 is constructed from a continuous length of resilient wire bent 65 together centrally of its length 7, thereby providing the two vertically disposed arms, respectively indicated at 8 and 9. The upper portions of the arms 8 and 9 are shaped 70 to form respective semi-circular head sections 10 and 11 which in combination constitute an annular head 12. The free ends of the head sections 10 and 11 overlap each other, as indicated at 13, at the top of the head 12.

The lower portion of the arms 8 and 9 are loosely turned around each other to provide a more rigid shank 14, and each of the arms 8 and 9 is formed with an offset portion, respectively indicated at 15 and 16, 80 disposed at the upper end of the shank 14.

The retention spring 6 is detachably connected in the tubular adaption rod 5 by inserting the shank 12 in the upper end of the latter. The retention spring 6 is maintained in position in the adaption rod 5 by 85 the tensional engagement of the offset portions 15 and 16 against the upper wall face of the rod 5, as clearly shown in Figure 3, 90 of the drawing.

The retention spring head 12 is disposed at the upper end of the adaption rod 5 and tensionally engages the inner wall face of the heating tube 2 for maintaining the adaption rod 5 in the operative position in the 95 latter. The contraction of the head 12 when engaging the heating tube 2 will automatically augment the tensional engagement of the shank 14 in the adaption rod 5, as shown in the Figure 1, of the drawing.

My improved retention spring is preferably made from comparatively heavy wire, and its construction provides a substantial structure which will not become distorted from use in the manner of retention springs 105 now in use.

What I claim is:

1. In an electrical hair waving apparatus including a heating tube and tubular adaption rod therefor, of a retention spring 110 detachably connected to said rod and having a split annular head adapted to tensionally

engage the inner wall face of said heating tube for normally maintaining said rod in position in said heating tube.

2. In an electrical hair waving apparatus including a heating tube and tubular adaption rod therefor, of a retention spring constructed from a continuous length of resilient wire and formed to provide a shank adapted for tensional engagement in the upper end 10 of said rod, said spring having its upper end formed to provide a split annular head adapted for tensionally engaging the inner wall face of said heating tube for normally maintaining said rod in position in said heating tube.

3. In an electrical hair waving apparatus including a heating tube and tubular adaption rod therefor, of a retention spring constructed from a continuous length of resilient wire formed to provide a shank and an open 20 annular head, said shank adapted to tensionally engage in said tubular adaption rod, the free ends of said resilient wire overlapping each other in the formation of said 25 annular head to permit of the tensional en-

gagement of the latter in said heating tube for normally maintaining said adaption rod in position in said heating tube.

4. In an electrical hair waving apparatus including a heating tube and tubular adaption rod, of a retention spring constructed from a continuous length of resilient wire bent together centrally of its length, and providing a pair of vertically disposed arms, the lower connected portion of said arms turned around each other to form a shank adapted for tensional connection in said tubular adaption rod, the free end portions of said arms overlapping each other and in combination forming an annular head 40 adapted to tensionally engage in the heating tube to normally maintain said adaption rod in position in said heating tube, the tensional engagement of said head in said heating tube increasing the tensional connection of said shank with said adaption rod, substantially as described and for the purpose set forth.

In testimony whereof I affix my signature.

EDWARD A. McGINNIS.
